RICHARD M. HOPKINS, OF NEW YORK, N. Y., ASSIGNOR TO AMERICAN DISTRICT TELEGRAPH COMPANY, OF JERSEY CITY, NEW JERSEY, A CORPORATION OF NEW JERSEY.

CONTACT DEVICE FOR VALVE SUPERVISORY SYSTEMS.

1,371,993.

Specification of Letters Patent. Patented Mar. 15, 1921.

Application filed December 26, 1916. Serial No. 138,948.

To all whom it may concern:

Be it known that I, RICHARD M. HOPKINS, a citizen of the United States of America, and a resident of New York, county of New York, and State of New York, have invented certain new and useful Improvements in Contact Devices for Valve Supervisory Systems, of which the following is a specification.

10 My invention relates to improvements in contact devices adapted for employment in valve supervisory systems—for example the systems of supervising shut-off valves of automatic sprinkler fire extinguisher systems. In these fire extinguisher systems, it is customary, during warm weather, to keep the pipes flooded with water, and therefore the shut-off valves to be supervised, are open, and it is desired to send a signal 15 in case any one of those valves should be closed. During cold weather it is customary to maintain the pipes empty, so that water may not freeze in them, and therefore in such case the shut-off valves are closed, and it is desired to send a signal in 20 case one of these valves is opened. My invention comprises a contact device adapted for attachment to a shut-off valve, which contact device will be operated either when 25 the valve is closed from its wide open position, or when the valve is opened from its completely closed position. My invention further comprises a suitable switch readily 30 operable from the outside of the contact device, whereby either of the two main contact devices may be placed in circuit at will.

The object of my invention is to provide 35 simple and reliable means whereby a signal may be sent, either in the event of complete or materially partial closure of a supervised valve, or upon opening, partially or completely, of such valve.

I will now proceed to describe my invention with reference to the accompanying 40 drawings, and will then point out the novel features in claims. In said drawings:

Figure 1 shows a side elevation of a valve provided with my improved contact device, and indicates a conventional method 45 of connection of such contact device to the valve.

Fig. 2 shows a front view of the contact device, with its cover plate removed.

Fig. 3 shows a longitudinal section of the

contact device on the line 3—3 of Fig. 2; 55 and

Fig. 4 shows a longitudinal section of the cover plate of the contact device.

In the drawings, 1 designates the valve itself. I have shown this valve as a gate 60 valve, of usual construction, but the particular type of valve employed is not material. To the bonnet flange of the valve is secured the case 2, of the contact device. This contact device comprises a stem 3, connected, in some suitable manner, (various suitable methods of connection are well known in the art) to the stem or operating member 4 of the valve, so that as that stem 4 is operated to open or close the valve 1, 65 the stem 3 of the contact device will be raised or lowered.

The stem 3 of the contact device carries a contact member 5 which, in the construction shown, has the form of a ring, which 70 contact member 5 will move up or down with the stem 3. In Fig. 2 I have shown this contact member 5 in an abnormal position, which may be reached under circumstances to be explained hereafter. Within 75 the case 2 are contact springs 6, 7 and 9. Under normal conditions contact 5 is always in contact with contact spring 6; and normally it will also be in contact either with spring 7 or with spring 9, according to the 80 season of the year. Another switch 8, to be referred to presently, determines whether spring 7 or spring 9 shall be in circuit. Spring 6 and switch 8 constitute terminals 85 of a normally closed supervisory circuit—a 90 circuit normally closed either through spring 7 or spring 9.

10 designates a spring tending to raise stem 3. If the contact device, or the connection of that contact device with the valve 95 should be tampered with, in such manner as to release, even momentarily, the stem 3, the spring 10 will force that stem upward, so as to break contact of contact member 5 with spring 6 and thereby the supervisory 100 circuit will be broken, which has the effect of setting an alarm signal.

11 designates a barrel, forming the actuating member of switch 8, rotatably mounted in the cover 12 of case 2, and corresponding in a general sense, to the tumbler barrel of a lock, though it is not provided with tumblers. It is provided, however, with a

key slot 13 of peculiar configuration, and a correspondingly formed key (not shown) if inserted in this slot 13, will provide means for rotating the barrel 11. At the two sides 5 of this barrel 11 are springs 14 and 15 adapted to make contact respectively with stationary contact members 16 and 17; of which, 17 is electrically connected to contact spring 7, and 16 is electrically connected to 10 contact spring 9. The barrel 11 is provided with a projection 18 whereby contact spring 14 may be brought into contact with contact member 16, or contact spring 15 may be brought into contact with contact member 17, according to the direction in which 15 the barrel 11 is turned. The cover is provided with limit projections 19 and 19' which, by engagement with a projection 21, carried by the barrel, limit the extent of 20 rotation of that barrel.

The base 20 to which springs 14 and 15 are connected or of which they form parts, constitutes, as to the contact mechanism, one terminal of the supervisory circuit; the 25 spring 6 constitutes another terminal of the supervisory circuit. It will be obvious from what has been said above, that when the barrel 11 is turned to bring contact members 15 and 17 into contact, then contact 30 spring 7 is in the supervisory circuit; and that when the barrel 11 is turned so as to bring contact members 14 and 16 into contact, then spring 9 is in the supervisory circuit.

35 With the valve wide open contact member 5 is in contact with springs 6 and 7 (contacts 15 and 17 being then in contact with one another); and the supervisory circuit is closed through contacts 6, 5 and 7. If 40 now valve 1 be closed, then during the early portion of the closing movement, and before the valve has been closed sufficiently to materially restrict flow, contact will be broken between 6 and 7 and therefore the 45 supervisory circuit will be opened; an alarm being thereby transmitted. If the closing of valve 1 be continued contact member 5 will soon reach contact member 9, but this member 9 being out of circuit, circuit conditions are not changed.

50 Supposing valve 1 to be completely closed, and contact member 9 to be in circuit; then a very slight opening of the valve will suffice to break contact between members 5 and 9, thereby opening the supervisory circuit and sending in a signal.

55 It is intended that valve 1 shall never be closed, except upon visit of an inspector, who will himself close the valve, in putting 60 the extinguisher system or the like into condition for cold weather, and such inspector, upon closing the valve, will also, by means of a suitable key, operate the switch barrel 11, so as to place contact member 9 in circuit. It is intended further that the valve

1, once closed, shall never be opened, partly or completely, except upon visit of an inspector, who will at such time, open the valve 1 himself, at the same time operating the switch barrel 11 by means of a suitable 70 key, so as to put contact member 9 out of circuit and put contact member 7 in circuit. If, at other times than upon such visits of the inspector, the valve be opened from its completely closed position, or be 75 closed, partly or completely, from its wide open position, a suitable signal will be sent through the supervisory circuit, as above explained.

What I claim is:

80 1. A valve supervising contact device comprising contacts, and means adapted to be operated by opening or closing of a valve to which said device may be connected for operating such contacts, one of said contacts being arranged to break a circuit through one contact upon partial or complete closure of the valve from wide open position, and to break the circuit through another contact upon partial or complete 85 opening of the valve from completely closed position thereof.

2. A valve supervising contact device comprising contacts and means adapted to be operated by opening or closing of a valve 90 to which said device may be connected for operating such contacts, one of said contacts arranged to send a supervisory signal upon partial or complete closure of the valve from wide open position, the other to send 95 a supervisory signal upon partial or complete opening of the valve from completely closed position thereof, and further contact means for placing one or the other of said first mentioned contacts in circuit at will. 100

105 3. A valve supervising contact device comprising contacts and means adapted to be operated by opening or closing of a valve to which said device may be connected for operating such contacts, one of said contacts arranged to send a supervisory signal upon partial or complete closure of the valve from wide open position, the other to send 110 a supervisory signal upon partial or complete opening of the valve from completely closed position thereof, and contact means adapted for key-operation and adapted to place one or the other of said first mentioned contacts in circuit at will. 115

120 4. A valve supervising contact device comprising contacts and means adapted to be operated by opening or closing of a valve to which said device may be connected for operating such contacts, one of said contacts arranged to send a supervisory signal upon 125 partial or complete closure of the valve from wide open position, the other to send a supervisory signal upon partial or complete opening of the valve from completely closed position thereof, and contact means com- 130

prising a rotary barrel adapted for key-operation and adapted to place one or the other of said first mentioned contacts in circuit at will.

5. A valve supervising contact device comprising an inclosing case, a stem therein adapted to be moved longitudinally by opening or closing of a valve to which the contact device may be connected, a contact member arranged to move with such stem, and three contact springs with which such contact member may make contact during such movement of such stem, said contact springs so arranged that the said contact

member will close contact between two of 15 said springs in one contact combination during movement of such stem from one extreme position, and will close contact between two such springs in another contact combination during movement of such stem 20 from another extreme position.

In testimony whereof I have signed this specification in the presence of two subscribing witnesses.

RICHARD M. HOPKINS.
